BY Perry S. Webster

ATTORNEY

UNITED STATES PATENT OFFICE.

RUSSELL E. VAUGHAN, OF WOODLAND, CALIFORNIA.

HAND NUTCRACKER.

Application filed May 7, 1924. Serial No. 711,595.

This invention relates to improvements in devices for cracking nuts, and particularly to a hand operated and relatively small sized machine for the purpose, such as would be very handy for the use of confectioners, and others who have occasion to crack small quantities of nuts at a time.

The principal object of my invention is to provide a device of this character so constructed that the nuts will be efficiently cracked without the danger of any of the kernels or meats being bruised, crushed or damaged in any way.

Another object is to construct the nut cracker in such a way that in a machine of a single size nuts of any size from a pine nut up to the largest walnuts or similar sized nuts may be cracked with equal efficiency.

20 A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views:

Fig. 1 is a sectional elevation of my improved nut cracker.

Fig. 2 is a cross section on the line 2—2 of Fig. 1.

35 Referring now more particularly to the characters of reference on the drawings, the numeral 1 denotes a cylindrical shell having end plates 2 and 3 respectively, this structure forming a complete enclosure except for diametrically opposed and vertically located intake and discharge orifices 4 and 5 respectively.

40 The end plate 2, which may be considered as being at the front end of the machine, has attached thereto a clamping structure 6 by means of which the machine may be removably attached to and suspended clear of a table 7 or the like.

Turnably mounted in the end plates is a 50 shaft 8 on the outer end of which, beyond the plate 2, is adjustably mounted a handle member 9. On the opposite outer end of the shaft is an adjustable collar 10. By adjusting the positions of the handle and collar on the shaft the setting of the shaft relative

to the end plates and the shell may of course be altered, as will be evident.

Fixed on the shaft inside the shell and adjacent the plate 2 is a disc 11, its inner face being provided with parallel ridges 12 throughout. Pivotal mounted on lugs 13 projecting inwardly from the plate 3 on opposite sides of the shaft 8 is another and what may be termed stationary disc 14, through which the shaft passes with sufficient clearance to allow of adjustment of said disc relative to the shaft without binding on the latter. The inner face of this disc, which is that face which is adjacent the ridged face of the disc 11, is provided with horizontal and transverse ridges 15 throughout these ridges being similar in size and spacing to the ridges 12.

The disc 14 is set in a plane at right angles to the shaft transversely of the shell, 75 but is adapted to have a slope from top to bottom, so that the disc 14 is closer to the disc 11 at its lower end than at the top. The angle or slope of setting of the disc 14 is adjusted at will by means of set screws 16 mounted in the end plate 3 above and below the shaft and pivotal bearings of the said disc, so that by advancing one set screw 80 and retracting the other the disc swings about its pivotal connections, thereby altering its angle relative to the disc 11.

The discs are set so that the intake and discharge openings 4 and 5 are therebetween. It will be noted that by adjusting the shaft 8 lengthwise the disc 11 may be 90 caused to be set as close to or as far away from the disc 14 as may be desired, depending on the size of nuts being cracked.

In operation the discs at their upper end are spaced far enough apart to freely accommodate the particular kind of nut to be cracked. The nuts are then fed through the intake opening 4 and passed between the two discs, the distance between which decreases from top to bottom, as has been 100 previously explained.

Upon rotating the handle the ridges 12 of the disc 11 constantly present a different setting relative to the ridges 15 on the fixed disc 14. As the nuts pass down between the discs the shells will sooner or later be gripped by the roughened surfaces provided by these ridges and before the nuts reach the discharge opening 5 the shells will 105 be cracked open and separated from the ker- 110

nels. The shells and kernels will then both drop out through the opening 5, when they may be of course easily segregated. It is of course essential for good results that the angle between the two discs shall not be so great that the meats are apt to be crushed between the discs at their lower ends. The proper setting, however, is something which the operator can accomplish with but very little experience.

To better enable a quantity of nuts to be fed into the machine with the least effort a hopper 17 of suitable size is preferably mounted on the shell 1 leading to the intake opening 4.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A nut cracker comprising a stationary plate provided on one face with transverse and horizontal ridges parallel to each other, a rotary plate provided with transverse ridges mounted in opposed and spaced rela-

tion to the first plate, the latter being normally disposed at an angle to the rotary plate.

2. A nut cracker comprising a casing having opposed end plates, a rough faced rotary plate turnable in the casing between the end plates, a shaft journaled in the end plates and secured to the rotary plate, a relatively stationary rough-faced plate disposed in opposed and spaced relation to the rotary plate, and horizontally opposed pivotal connection and supporting means between said stationary plate and adjacent end plate of the casing, whereby to permit the shaft passing through the stationary plate to the adjacent end plate.

3. A nut cracker comprising a casing having opposed end plates, a rough-faced rotary plate turnable in the casing between the end plates, a shaft journaled in the end plates and secured to the rotary plate; a relatively stationary rough-faced plate disposed in opposed and spaced relation to the rotary plate, transversely opposed ears projecting from the back of the stationary plate, lugs alined with said ears projecting theretoward from the adjacent end plate of the casing, and horizontal and separate pivots through said ears and lugs, the shaft passing through the stationary plate to the adjacent end plate between the ears, lugs and pivots.

In testimony whereof I affix my signature.
RUSSELL E. VAUGHAN.
